UNITED STATES PATENT OFFICE

FRANK W. COLLINS, OF CORTLAND, NEW YORK.

DESIGN FOR A STOVE.

SPECIFICATION forming part of Design No. 23,708, dated October 16, 1894.

Application filed July 12, 1893. Serial No. 480,320. Term of patent 7 years.

To all whom it may concern:

Be it known that I, FRANK W. COLLINS, a citizen of the United States, and a resident of Cortland, in the county of Cortland and State of New York, have invented a certain new and useful Design for Heating and Ventilating Stoves, of which the following is a specification, reference being also had to the accompanying drawing, fully representing the same.

The leading features of my design consist of the following:—

First. A nickel plated cover, A, rectangular at the base and rising thence in semi-spherical or dome-like form, around the base a broad band of plain, polished nickel with row of beading above, and above this a spray or leaf-like design raised and polished, with unpolished nickel between, serving to bring out the design, all as shown and described.

Second. A nickel plated and polished section or top B, of open or perforated scroll work, beneath the cover A, and covering and substantially concealing from view the magazine of the stove, harmonizing in its outlines and ornamentation with the cover A above, forming with it an ornamental top to the stove. Said perforated top B has a jewel set in the middle of the front. Said top B extends outward and slopes gradually away from said cover A, and then, curving slightly inward, swells and curves outward beyond its first extension, and rests upon the foliated band, C. The first extension of the section B is smooth and polished throughout, except that small grooved channels of unpolished nickel radiate outward from the bottom of the cover A nearly to the edge of the extension, these channels being joined together in pairs at the ends near the edge of extension by similar channels running at right angles thereto.

The open work section B is separated into four panels, one on each side of the stove, by a plain, polished nickel band running around the open work and widened at the four corners of the section, all as shown and described.

Third. Beneath the open work section B and beneath the doors F, F, F, and G, G, G, the three bands, C, C, C, foliated or ornamented with overlapping leaves, surmounting a plain narrow edge extending around the stove, all as shown.

Fourth. Beneath the upper band C, the

curved or partly spherical, ornamental piece D, with plain edge and ornamental scroll center, projecting till it comes into the plane of the doors and furnishing a stop or rest for the same, all as shown.

Fifth. At the side of D, and extending around the stove, and up and down near the edges of each side thereof, separated at the corners by plain vertical edges, the leaf, bud and fruit work in relief, E, E, all as shown.

Sixth. The doors, F, F, F, G, G, G, the former being the upper and the latter the lower mica doors of the stove. These doors are of peculiar or double design, the foundation skeleton, or portion supporting the mica being in rectangular sections, grooved and studded with half round turnings or projections. Upon this foundation is laid the ornamental or decorative scroll work. The doors are surrounded or edged with transverse beading, all as shown.

Seventh. A nickelized and polished hood H, harmonizing with the other nickel work of the stove, covering the ash-pit door, swelling out from top and ends of same, and bearing the words, "Howe Ventilator," and the numbers, "42," "44" or "46" according to size of stove, all as shown.

Eighth. The polished and nickelized foot-rails and brackets I, I, composed of three parts, the brackets and rails perforated, and both brackets and rails ornamented in scroll work to harmonize with other ornamentation of the stove, all as shown and described.

Ninth. The ash-pit bottom J, ornamented at each front upper corner with raised rectangular work, and on the four sides with vertical, raised design, with plain, narrow band above and below, all as shown.

Tenth. The lower bottom K, forming a broad, plain band below ash-pit bottom J.

Eleventh. The skirt L, L, and legs M, M, with surfaces of polished and nickelized raised work, harmonizing with other ornamental work of the stove, all as shown and described.

The design is provided in part by casting, and in part by burnishing, polishing, nickel-plating, &c., and the process will be understood when the product is described.

What I claim is—

1. In a design for a stove, the dome section showing a rectangular base having a wide

polished flat nickel plated band, a row of beading in the rectangle above this band, and a flattened dome with a raised polished spray of leaf like forms, separated by lines of unpolished nickel, substantially as shown and described.

2. In a design for a stove, the generally rectangular top section B of open scroll work, with a jewel at the front, the top section extending outward below the dome, then curving inward, then at a lower plane curving outward beyond the first extension, then terminating in the foliated band C, said section having plain polished bands at the corners, substantially as shown and described.
3. In a design for a stove the upper door section having the swell above the double

doors which are curved to correspond, and have surface ornamentation substantially as shown and described.

4. In a design for a stove, the ash pit section terminating at the ends in projecting brackets and having the surface ornamentation substantially as shown and described.

5. The design for a stove substantially as shown and described.

Signed at Cortland, in the county of Cortland and State of New York, this 16th day of June, A. D. 1893.

FRANK W. COLLINS.
